Atty's.

UNITED STATES PATENT OFFICE.

OTTO NELSON, OF CHICAGO, ILLINOIS.

DIESTOCK.

1,403,519.

Specification of Letters Patent. Patented Jan. 17, 1922.

Application filed September 15, 1920. Serial No. 410,381.

To all whom it may concern:

Be it known that I, OTTO NELSON, a citizen of the United States, residing at Chicago, in the county of Cook and State of Illinois, have invented certain new and useful Improvements in Diestocks, of which the following is a specification.

My invention relates to die stocks and has for one of its objects the provision of a simple and efficient die stock for holding a plurality of dies capable of being brought quickly and easily into use.

A further object is the provision of a die stock having an opening with a plurality of dies adapted to be brought into registration with the opening.

A further object is the provision of a die stock having a substantially central opening with a plurality of dies each adapted to be brought into registration with said opening and a guide having guide openings adapted to be brought into registration with the opening in the die stock.

Other objects will appear hereinafter.

An embodiment of my invention is shown in the accompanying drawing, forming a part of this specification, and in which—

Fig. 1 is a plan view of a die stock embodying my invention;

Fig. 2 is an edge view of the same;

Fig. 3 is a bottom view of the same;

Fig. 4 is a section taken on line 4—4 of Fig. 1; and

Figs. 5, 6 and 7 are views similar to Fig. 4 but showing different forms of portions of the die stock.

Referring more particularly to the drawing, I have indicated a die stock 8 of channel form in order to provide a guideway 9. In the guideway 9 I mount a die block 10. The die block 10 is elongated and provided with a plurality of openings 11 in which dies 12 are mounted.

The guideway 9 may be formed in any desirable manner so as to hold the block 10 in position for sliding longitudinally of the die stock. In Figs. 1 and 4 I have shown flanges 13 on the edges of the guideway 9 which extend over on the front side of the block 10 to hold it against lateral movement out of said guideway. It will be apparent

that in this form the flanges 13 extend over onto the dies 12 also holding them in position in the block 10. In Fig. 5 I have indicated the flanges 13 as being narrower and not covering the dies 12. The dies 12 are held in the block 10 by flanges 14 formed on said block. In Fig. 6 I have shown tongues 15 on the stock 8 in the guideway extending into grooves 16 in the die block 10. In Fig. 7 I have shown the engaging surfaces of the guideway 9 and block 10 as being curved which would prevent lateral movement of the block out of the guideway 9. From this it will be apparent that many forms of guideway may be provided. An essential thing of this invention is providing a suitable connection between the guideway and block so that the block can be slid easily in the guideway.

The die stock is preferably made in a length so that the block 10 can be slid so as to bring each of the dies 12 into operative position in registration with an opening 17 in the back of the die stock. The block 10 may be held against longitudinal movement in the guideway in any desirable manner. As a simple means I have shown a screw 18 threaded in a thickened portion 19 of the guideway and adapted to extend through openings 20 in the block 10 so that the inner end of screw 18 can engage a recess 21 in each of the dies 12. It will be apparent that by unscrewing screw 18 until the block 10 can be slid along until the proper die can be brought opposite the opening 17 and screw 18 run through opening 20 such die can be locked so as to be operable by the die stock.

Sometimes it is desirable to slightly change the size of a round solid die, such as those indicated. In such cases I provide an opening 22 in one side of the guide 9 opposite the screw 18 so that a screw driver or other implement, not shown, may be inserted through the opening 22 and a corresponding opening 24 in block 10 to adjust the die 12. Sometimes the slotted portion 23 of a die will not be directly opposite its recess 21 and in such cases screw 18 is backed up until the die is free to be turned around to bring slot 21 in registration with opening 22. The block 10 is provided with an opening 24 at

each die 12 so as to make each of the dies capable of being adjusted without its being taken from the die stock.

It is sometimes desirable to provide a guide on the die stock for facilitating starting the threads straight. I have, therefore, indicated a guide block 25 pivoted at its center on the back of the die stock 8 having a plurality of openings 26 therein corresponding in size and number to the size and number of dies 12 in block 10. I have shown six dies 12 and openings 26, but it will be apparent that the number may be changed as desired. The block 25 is held in proper position to bring the openings 26 in registration with opening 17 in any desirable manner, such as by notches 27 in which a spring-pressed bolt 28 is adapted to engage. It will be apparent that by withdrawing the spring bolt 28 by the handle 29 the block 25 can be turned manually to bring any one of the openings 26 into registration with opening 17 and locked in such position by simply releasing the handle 29, permitting the spring bolt 28 to automatically move into the proper notch 27.

As a convenience I provide pins or screws 30 at the ends of the die stock 8 to prevent the block 10 from sliding out of the guideway when not held by the screw 18. Any other desirable means may be used for this purpose. It will also be apparent that by removing one of screws 30 the block 10 can be taken out of the guideway and other dies 12 placed in the block. Of course when the dies 12 are changed a block 25 with corresponding openings 26 must be put in place on the die stock.

In Fig. 1 I have indicated a block 31 in the channel at one end of the die stock 8 to close the channel. It will be apparent that the blocks 31 are used or not, as desired, their only function being to give the stock a more finished appearance.

In Figs. 4 and 6 I have indicated grooves 32 under the dies 12 in the stock 8 to provide clearance for chips cut out by the dies in use. By providing grooves, such as indicated, chips which would catch and wedge between the die and stock would either fall out through the groove 32 or else be broken so that they would not interfere with the free sliding of the block in the die stock.

55 I claim:—

1. In combination, a die stock of channel form having a central opening therein; a die block movably mounted in said die stock; a plurality of dies in the die stock; and a guide block movably mounted on the die stock with a plurality of guide openings adapted to be brought into registration, one at a time, with the opening in the die stock.

2. In combination, a die stock of channel

form having a central opening therein; an elongated die block slidably mounted in said die stock; dies in said die block; and a guide block mounted on the die stock with guide openings therein adapted to be brought into registration with the dies in 70 the die block.

3. In combination, a die stock having a guideway therein and a central opening; an elongated die block slidably mounted in said guideway; a plurality of alining dies in said die block, the latter being adapted for movement to bring each of the dies into registration with the opening of said die stock; and a guide block on the die stock with a plurality of guide openings therein adapted 80 to be brought into registration with the opening in the die stock.

4. In combination, a die stock having a guideway and central opening therein; an elongated die block slidably mounted in 85 said guideway; and a plurality of dies loosely mounted in the die block in a line, there being portions of the die stock engaging the sides of said dies holding the latter in said die block.

5. In combination, a die stock having a guideway and central opening therein; a plurality of dies mounted in said guide; and a guide block pivoted on the die stock with a plurality of guide openings disposed 95 in a circle about the pivotal point of the guide block and each of said guide openings being adapted to be brought into registration with the opening of the die stock upon pivotal movement of the guide block. 90

6. In combination, a die stock having a central opening therein; a plurality of dies movably mounted in said die stock; a guide block pivoted on the die stock with a plurality of guide openings arranged in a circle about the pivotal point of said guide block; and locking means adapted to lock the guide block in positions where each of said guide openings, one at a time, are in registration with the opening in said die 105 stock.

7. In combination, a die stock having a guideway therein; a die block mounted in said guideway; a plurality of dies mounted in the die block, there being openings in the die block laterally of the latter at each of the dies; and a screw threaded in the die stock and passing through one of said openings in the die block to lock a corresponding die against rotary movement in the die 120 block.

8. In combination, a die stock having a guideway therein with openings extending transversely through the sides of said guideway; an elongated guide block slidably mounted in the die stock and having lateral perforations therein adapted to be brought into registration with the openings in said

guideway; a plurality of dies in said die block adjacent the openings in the latter; and a screw threaded in one of the openings in said guideway adapted for holding the dies, one at a time, against rotary movement in the die block, the other opening in said guideway being adapted to gain access

to the opposite side of the die from that engaged by said screw when the latter is locking such die against rotary movement. 10

In testimony whereof I have signed my name to this specification on this 13th day of September, A. D. 1920.

OTTO NELSON.
